UNITED STATES PATENT OFFICE.

HARRY TUTTLE, OF CONNERSVILLE, INDIANA.

TIRE-HOLDER.

1,106,755.

Specification of Letters Patent. Patented Aug. 11, 1914.

Application filed May 15, 1913. Serial No. 767,819.

To all whom it may concern:

Be it known that I, HARRY TUTTLE, a citizen of the United States, residing at Connerville, in the county of Fayette and State of Indiana, have invented a new and useful Improvement in Tire-Holders, of which the following is a specification.

My invention relates to certain new and useful improvements in tire-holders, and is 10 fully described and explained in the specification and shown in the accompanying drawings, in which:—

Figure 1 is an elevation of my improved tire-holder showing the same in its operative position; Fig. 2 is a section on the line 2 of Fig. 1; Fig. 3 is a section on the line 3 of Fig. 2, Fig. 4 is a view of the clamping-means, taken from the same direction as Fig. 3, but with the parts in an alternative 20 position for holding two tires, and Fig. 5 is a perspective view of my improved tire-holder.

Referring to the drawings, 5 is a semi-circular band of metal to which are secured, 25 preferably by rivets, three plates 6, 7 and 8, respectively. The plates 6 and 7 are provided with integral brackets 9 which extend from them to the body of the car, (Fig. 2), to which they are bolted or otherwise secured, these brackets forming the means for supporting the entire structure. To secure greater stiffness, the plates 6 and 7 are connected together by a strut 10. Aside from these brackets and the attaching 30 means for the strut 10, the three plates 6, 7 and 8 are in all respects alike, and reference will now be had more especially to the plate 6, which is shown in Fig. 2. This plate, it will be seen, like the others, is provided with two inwardly-extending ears 11 and 12, one on each side of the plate, and the two ears being displaced circumferentially so that the ears are in staggered positions. This construction enables clips to be 45 mounted on the ears in position to hold one or two tires. Each ear is centrally perforated and screw-threaded to receive the threaded end of a bolt.

13 and 14 are two clips, each of which 50 consists of a cylindrical portion perforated to receive the bolt which enters the corresponding ear 11 or 12, as the case may be, and a hooked portion adapted to engage the edge of a rim such as is commonly used in 55 connection with demountable tires. As

shown in Figs. 2 and 3, each clip lies on that side of the corresponding ear which is nearest to the center of the plate. When so arranged, the hooked parts of the clips are just at the proper distance that when the 60 bolts holding the clips in position are tightened up, the clips will tightly engage and hold a single demountable rim of standard form. However, if it be desired to carry two tires and rims, each clip can be taken 65 off by unscrewing its attaching bolt and can be placed on the opposite side of the corresponding ear, that is, on the side of the ear farthest removed from the center of the plate, and in this case the hooked parts of 70 the two ears will be just far enough apart to engage and firmly grip the opposite margins of two demountable rims placed side by side. By this means, therefore, a peculiarly simple and firm device is provided wherein 75 one or two tires with their connected rims can be placed and from which they can be released with a minimum of effort.

A particular advantage of the present structure is that when carrying a single tire, 80 the structure has a complete and finished appearance on the car, and in no way suggests to the observer that it is a holder for two tires only half filled, while when carrying two tires there is no suggestion in appearance that the structure is a make-shift. 85 In the devices commonly employed for analogous purposes holders are made either for one or two tires, and if a single holder is made to carry two tires it is only by some 90 make-shift contrivance, while if a double holder is used for a single tire the appearance is equally unsatisfactory.

I realize that considerable variation is possible in the details of construction herein 95 shown, and I do not intend to be limited thereto, except as pointed out in the following claims, in which the intention is to claim all the novelty inherent in the structure described as broadly as is permitted by the 100 state of the art.

What I claim as new and desire to secure by Letters Patent, is:

1. A tire-holder comprising members supported from a vehicle body, said members 105 including stationary parts disposed in different planes and movable clamps to engage the opposite edges of a rim on which a tire is supported, each of said clamps having a portion lying against one of said stationary 110

members and an extended portion forming a clip which terminates adjacent to the edge of the rim, whereby the clips will be disposed in staggered relation on opposite sides of said rim and at an extended or diminished distance from the stationary parts, for the purpose set forth.

2. In a tire-holder, two clips to engage rim edges, and means disposed in different planes to support said clips alternatively with their operative parts at two different distances apart, whereby to grip the opposite edges of a single rim or of two rims placed side by side.

3. In a tire-holder, two clips to engage rim-edges, stationary parts carried by the vehicle body having their corresponding faces in different planes, and means to support each of said clips, at will, on either side of one of said stationary parts, whereby the operative ends of said clips may be spaced at different distances, for the purpose set forth.

4. In combination, a semi-circular member, plates secured thereto and receiving support from the vehicle body, ears disposed in different planes upon said plates, and clips bolted to said ears to be engaged with oppo-

site rim-edges and in staggered positions thereon, for the purpose set forth.

5. In combination, a semi-circular member, plates thereon, ears upon said plates having their corresponding faces in different planes, clips to engage rim-edges and adapted, at will, to be secured to either face of said ears, whereby their operative ends may be spaced at distances apart to grip the opposite edges of a single rim or two rims placed side by side.

6. In combination, an upwardly-convex semi-circular member, plates at the ends thereof secured to the vehicle body, a similar plate at the upper part thereof, ears secured to said plates having their corresponding faces in different planes, and clips to be secured to said ears each, at will, upon either face thereof, whereby their operative ends lie at different distances apart, for the purpose set forth.

In testimony whereof I have hereunto set my hand this 22nd day of April, 1913.

HARRY TUTTLE.

In presence of—

CLARENCE LORILLARD,
HOWARD M. WYLIE.
